UNITED STATES PATENT OFFICE.

BERTRAM A. STROOCK, OF NEWBURGH, NEW YORK.

PRINTED TAPESTRY.

Application filed January 2, 1923. Serial No. 610,326.

To all whom it may concern:

Be it known that I, BERTRAM A. STROOCK, a citizen of the United States, residing at Newburgh, in the county of Orange and State of New York, have invented certain new and useful Improvements in Printed Tapestries, of which the following is a specification.

My present invention relates to the production of a fabric giving the effect of hand-woven tapestry or needle point, which fabric is produced by printing the desired design on a plain fabric which is of special weave, so that by the combination of this special 10 weave and the printing, the desired effect may be produced.

As is well understood, hand-woven tapestries and needle point are made by working the design in properly colored yarns, which 20 yarns are held in place either by a previously woven fabric or by strands in the nature of a warp. This is done in such manner as to produce the design on the surface of the tapestry with stepped lines instead of 25 straight or curved lines, at the margins of the figures of the design. By my present invention, I produce tapestry effects similar to those produced by the hand-weaving or needle point methods without the time and 30 expense involved in the hand method.

In the accompanying drawings, Fig. 1 is a plan, on an enlarged scale, of a portion of an illustrative form of plain fabric which I may use as a base for the printed tapestry; 35 Fig. 2 is a section on the line 2—2 of Fig. 1; Fig. 3 is a section on the line 3—3 of Fig. 1, and Fig. 4 is a plan of a portion of the printed tapestry showing the effect produced.

40 Like reference characters indicate like parts in the several views.

In producing the plain fabric which is to be used as a base for the printing to produce the tapestry effect, I preferably use the 45 weave illustrated in Figs. 1, 2 and 3, in which relatively heavy, soft, loose-twisted yarn filler strands 10, preferably of wool, are held between interwoven fine, hard-twisted filler strands 11 and fine, hard-twisted warp 50 strands 12 and 13. The warp strands 12 and 13 pass respectively below and above the filler strands 10 and above and below the intermediate filler strands 11, so that each warp strand 13, for instance, passes over 55 each filler strand 10.

The warp strands 13 are spaced apart a

distance approximating the diameter of the soft filler strands 10 and preferably the warp strands 12 are similarly spaced. The warp strands 12 and 13 are drawn down into 60 the body of the filler strands 10, so that a series of squares are formed on the surface of the fabric, each square being determined by the space between a pair of warp strands 13 and a pair of intermediate filler strands 65 11. In Fig. 2, the warp strands 13 are shown drawn down into the body of the strands 10 and the undulations produced in these strands by the warp strands are shown best in Fig. 3. It will be noted by reference 70 to Fig. 3 that not only is the surface of the fabric formed into squares, but the soft yarn constituting the strands 10 is pushed up into small projections between each pair of warp strands. The formation of these projections 75 or mounds is accentuated by the tension on the warp strands on the opposite side of the fabric.

In some tapestry effects which I have produced, the plain fabric is woven with the 80 strands 11, 12 and 13 in black cotton yarn, and the soft strands 10 in wool having some suitable body or background color, which color may be the original color of the yarn or may be obtained by dyeing the fabric 85 after it is woven.

The next step in the production of the tapestry effect is the printing. This may be carried out in the usual manner of printing on fabrics, as by means of blocks, each 90 arranged to give the desired outline in the desired colors, and I have found that no great care need be used in applying the colors to the fabric in order to produce the peculiar "stepped" formation of the lines 95 of the design as such lines appear in hand-woven tapestries and needle point, and as is shown in Fig. 4. This is due to the fact that the small squares formed in the soft, loose-twisted strands 10 absorb the ink 100 readily, but that the "running" of this ink in these strands stops at the lines at which a strand 10 is compressed by warp strands, or, in other words, at the edges of the squares. Consequently, if block printing is 105 used, for instance, and the edge of the printing block strikes any portion of one of the squares, that square tends to become completely colored, but, on the other hand, the coloring from that square does not run 110 into an adjacent square. Consequently the stepped effect indicated at 14 in Fig. 4 will

be produced, no matter how the lines on the printing surface or the like registers with the squares of the fabric. It will be understood, of course, that in practice, the 5 "stepped" appearance of the lines is not as exact nor as complete as it would be in hand-woven tapestries or needle point, but such "stepping" occurs with sufficient regularity in my fabric to give the general appearance of hand-woven tapestry or needle point.

I claim:

1. A fabric having the appearance of hand-woven tapestry or needle point, comprising interwoven fine, hard-twisted warp strands and alternate fine, hard-twisted and heavy, loose-twisted filling strands, with the heavy filling strands divided into squares by the warp strands and with the heavy 15 strands projecting above the warp strands between each pair thereof on the same side of the fabric, said fabric having a design printed on the projecting portions of the heavy filling strands with the lines of the 20 design following approximately the boundaries of said squares.
2. A fabric having the appearance of hand-woven tapestry or needle point, comprising interwoven fine, hard-twisted warp 25 strands and heavy, loose-twisted filling strands, with the heavy filling strands divided into squares by the warp strands and with the heavy strands projecting above the warp strands between each pair thereof on 30 the same side of the fabric, said fabric having a design printed on the projecting portions of the heavy filling strands with the lines of the design following approximately the boundaries of said squares.
3. A fabric having the appearance of hand-woven tapestry or needle point, comprising interwoven fine, hard-twisted warp

strands and alternate fine, hard-twisted and heavy, loose-twisted filling strands, the warp strands passing over the heavy filling 45 strands and under the fine filling strands and being drawn down into the heavy filling strands to produce projections of the heavy filling strands between each pair of warp strands on the same side of the fabric, and the warp strands on the same side of the fabric being spaced apart a distance equal approximately to the diameter of the heavy filling strands, said fabric having a 50 design printed on the projecting portions of the heavy filling strands with the lines of the design following approximately the boundaries of said projections.

4. A fabric adapted to be used in the production of printed tapestry or needle 55 point, comprising interwoven fine, hard-twisted warp strands and heavy, loose-twisted filling strands, with the warp strands passing over the heavy filling strands and spaced apart approximately the 60 diameter of the heavy strands to form squares on the surface of the fabric and with the heavy strands projecting above the 65 warp strands between each pair thereof.

5. A fabric adapted to be used in the production of printed tapestry or needle point, 70 comprising interwoven fine, hard-twisted warp strands and alternate heavy, loose-twisted and fine, hard-twisted filling strands, with the warp strands passing over the heavy filling strands and under the fine filling strands and spaced apart approximately 75 the diameter of the heavy strands to form squares on the surface of the fabric and with the heavy strands projecting above the 80 warp strands between each pair thereof.

BERTRAM A. STROOCK.
